U.S. Cl. D9—42

FIG. 4

FIG. 2

FIG. 1

FIG. 3

FIG. 5

FIG. 1 is a side elevational view of a combined jug and cap therefor embodying my new design, the opposite side being a mirror image of the side shown;

FIG. 2 is an end elevational view;

FIG. 3 is an end elevational view looking from the right of FIG. 1 and showing the end opposite that seen in FIG. 2;

FIG. 4 is a top plan view; and

FIG. 5 is a bottom plan view.

The dominant features of my design reside in the jug portions as shown in the drawing.

I claim:

The ornamental design for a combined jug and cap therefor, as shown and described.
